UNITED STATES PATENT OFFICE.

FRANK JOSHEP SCHWARTZ, OF LONGVIEW, ILLINOIS.

CHEST FOR TOOLS.

SPECIFICATION forming part of Letters Patent No. 739,451, dated September 22, 1903.

Application filed May 27, 1903. Serial No. 159,007. (No model.)

To all whom it may concern:

Be it known that I, FRANK JOSHEP SCHWARTZ, a citizen of the United States, residing at Longview, in the county of Champaign and State of Illinois, have invented a new and useful Improvement in Chests for Tools, of which the following is a specification.

My invention relates to tool-chests, and has for its objects to produce a device of this character containing a plurality of movable compartments for the reception of different classes of tools, in which the said compartments are so connected operatively with the chest lid or cover that when the latter is opened the various compartments will be automatically moved to positions for displaying the tools which they contain and permitting ready access thereto, and one in which the operation of closing the lid serves to automatically return the compartments to their normal positions prior to the complete closing of the lid, whereby it may be seen that the compartments are in their proper positions before final sealing of the chest.

With these and other objects in view the invention comprises the novel details of construction and combination of parts more fully hereinafter described.

In the accompanying drawings, Figure 1 is a perspective view of my improved chest open. Fig. 2 is a diagrammatic view showing the position of the parts when the chest is open. Fig. 3 is a perspective view of the chest partly closed and the compartments fully closed. Fig. 4 is a view similar to Fig. 2, the parts being in closed position.

Referring to the drawings, 1 indicates the body of my improved chest, which is composed of a front wall 2, a rear wall 3, end walls 4 and 5, and a bottom 6.

7 indicates the lid or cover, which is pivoted to the body, as at 8, and consists of a front wall 9, a rear wall 10, end walls 11 and 12, and a top 13, said cover being divided by a central longitudinal partition 14, to which latter is pivoted or hinged, as at 15, a movable compartment 16, herein termed the "saw-compartment," while there is also hinged to the partition, as at 17, a movable compartment 18, herein termed the "bit-compartment." These compartments 16 18 nominally

lie closed within the cover 7 and are swung outward therefrom simultaneously with the raising of the cover in the manner presently explained. The compartment 18 is provided at each end with a movable latch-bolt 19, which normally engages a keeper 20, carried by the rear wall 10 of the cover. The bolt 19 is automatically snapped into engagement with the keeper when the compartment moves to closed position by means of an actuating-spring 21, the bolt being provided with a finger 22, which operates in a slot 23, formed in the end wall of the compartment. The finger 22 is engaged for automatically withdrawing the bolt from its keeper in the manner herein-after described.

The body of the chest is provided with a fixed compartment 24, herein termed the "plane-compartment," and with a movable compartment 25, herein termed the "gage-compartment," and with a second movable compartment 26, herein termed the "miscellaneous" compartment, which latter is hinged or pivoted to the front wall 2 of the chest, as at 27. In fact, the upper half of the wall 2 constitutes the bottom of the compartment 26.

The saw and bit compartments 16 18 are opened and closed automatically and simultaneously with the opening and closing of the lid 7 by means of suitable link connections between said compartments at each end and the respective ends of the chest, and inasmuch as these link connections are exact duplicates at each end of the chest I will describe but one in detail. In these link connections, 28 indicates a primary link which is pivoted, as at 29, to the end wall of the cover and at 30 to the end of compartment 18 and is provided with a fixed curved arm or extension 31, connected by a link 32 with the saw-compartment 16. The arm 31 is pivotally connected with the link 32 by a rivet or the like, 33, traveling in a slot 34, and the link is in turn pivoted at 35 to the end wall of the lid or cover 7 and is further connected to compartment 16 by a slot-and-stud connection, as at 36. The compartment 18 is connected with the body of the chest by means of a pair of links 37 38, which are pivoted together at 39, the link 37 being pivoted to the end wall of the compartment at the point 30 and the link 38 to the

end wall of the chest at 40. The inner end of the link 37 is beveled or inclined to form a cam-face 41, the purpose of which will hereinafter appear.

- 5 42 is a latch-link pivoted at 43 to the link 38 and provided at its free end with a notch 44, which when the parts are in open position engages with a stud or keeper 45, carried by the end wall of the chest, the latch 42 being 10 held into engagement with the keeper by means of a spring 46, mounted upon a curved guide-arm 47, secured to the link 38 and sliding in a perforated stud or ear 48, carried by the latch-link 42. The link 42 is eccentrically 15 pivoted and is provided at its upper end with an inclined or cam face 49, which during the closing of the cover 7 is acted upon the cam-face 41 of link 37 to release to notch 44 from the keeper 45, as will be readily understood, 20 the arm 42 being automatically moved to latching position by the spring 46 when the parts are in the opened position.

- For actuating the movable compartments 25 26 to open and close them automatically 25 and simultaneously with the opening and closing of the cover and other compartments I provide a system of links comprising a primary link 50, pivoted at 51 to a transverse partition 52, mounted in the body of the chest. 30 This link is connected at its upper end by a strap 53 with the movable bit-compartment 18, the strap being pivoted to the compartment at 54 and held in engagement with the link 50 by transverse pins 55. The link 50 is connected by an intermediate link 56 with a secondary link 57, pivoted at 58 to the partition 52 and at its outer end, as at 59, to a link 60, which is in turn pivoted at 61 to the end wall of the compartment 26. 35 40 The compartments 25 26 are hingedly or pivotally connected, as at 62, and the compartment 25 is provided with a stud 63 of cylindrical form, which projects outward from its end wall and travels in a curved guideway 64, formed upon the inner face of the end wall 5 of the chest-body.

- 65 is a guide plate or member which is secured by screws or otherwise to the partition 52 and has a longitudinal channel 66, in which 45 is loosely mounted a spring 67, through which extends a rod 68, pivoted at its outer end, as at 69, to the lower end of the link 50 and provided with bearing arms or members 70 71, disposed at opposite ends of the spring 67. 55 When the parts are in the open position, as in Fig. 2, the head 70 bears upon the outer end of spring 67 and compresses the same against the inner end of the guide-channel 66, and with the parts in this position movement of the lid 7 toward closing position causes the curved arm 31 of link 28 to move in the direction indicated by the arrow, which swings the link 32 upon its pivot and causes its outer end to swing inward in the direction 60 of the arrow, moving the compartment 16 into the cover. At the same time the link 28 swings

inward in the direction of the arrow thereon, moving the compartment 18 inward to its position within the cover and causing the links 37 38 to break joint at their pivotal point and 70 the cam-face 41 to actuate the latch-arm 42, as above described. As the compartment 18 swings inward it exerts a pull upon the upper end of lever 50 through the medium of strap 53, which action moves the lower end of said 75 lever in the direction of the arrow thereon and through the medium of links 56, 57, and 60 swings the compartment 26 inward upon its pivot in the direction indicated by the arrow, which movement causes said compartment, 80 through its pivotal connection with compartment 25, to move the latter inward and downward, the latter being guided in such movement by stud 63, traveling in guide 64, until the parts reach the position illustrated in Fig. 3, 85 at which time the lid or cover 7 will be but half closed, thus permitting inspection of the compartments to be sure that there is no disarrangement of the parts prior to final and complete closing of the cover. In this connection it is to 90 be noted that as the lever 50 swings upon its pivot 51 during the closing operation it draws the rod 68 outward, moving the head 70 away from the spring 67 and permitting the same to expand, which action of the spring materially assists the operation and relieves the operator of any undue exertion or output of strength in manipulating the device. To 95 toward the final of the opening movement the head 71 on the rod 68 comes in contact with the spring 67 and again compresses the same, whereby it will be in condition to assist in the closing of the device. When the device is closed, as in Fig. 4, and it is desired to 100 open the same, the lid 7 is grasped and raised 105 and a reversal of the above-described movements follows; but it is to be noted in this connection that at the beginning of the opening operation the link 38 engages the finger 22 of the latch-bolt 19 and withdraws the latter 110 from its keeper 20 to release the compartment 18 and permit the latter to swing freely to open 115 position.

72 72 are a pair of rubber blocks attached to the wall of compartment 26, as seen in Fig. 115 3, and adapted when the chest is closed to bear upon the outer wall of compartment 16 for pressing same securely to position in the lid. These blocks serve the additional function of preventing the lid entirely closing except 120 when pressure is applied upon the same. By this means the lid of the chest, which latter is provided with a spring-lock, (not shown,) may remain in substantially closed position without the lock springing into engagement there- 125 with.

From the foregoing it will be seen that I produce a device which is simple of construction, efficient in operation, inexpensive to produce, and one which in practice will admirably perform its functions for the attainment 130 of the ends in view; but it is to be understood

that I do not limit myself to the precise details herein shown and described, inasmuch as various changes may be made therein without departing from the spirit or scope of my invention.

Having thus described my invention, what I claim is—

1. The combination with a chest having a pivoted lid or cover, of a plurality of pivoted compartments, mechanism actuated by the opening or closing of the lid to automatically move the compartments to open or closed position, a latch member operable for automatically locking the parts in open position, and means for automatically releasing the latch at the beginning of the closing movement.
2. The combination with a chest having a pivoted lid or cover, of a plurality of pivoted compartments, link connections between said parts operable by the opening or closing of the lid to automatically move the compartments to open or closed position, and a latch member operable for automatically locking the parts in open position, one of the links being provided with a cam-face acting upon the latch member during the closing movement of the cover to automatically release the same.
3. The combination with a chest having a pivoted lid or cover, of a pivoted saw-compartment and a pivoted bit-compartment car-

ried by the lid and closing therein, a latch-bolt carried by the bit-compartment for automatically locking the same in closed position, and link connections between said parts for automatically opening and closing the compartments by the opening and closing of the lid, one of said links being adapted to actuate the latch during the opening movement of the lid to automatically release the bit-compartment.

4. The combination with a chest having a pivoted lid or cover, of a pair of pivoted movable compartments carried by the lid, a pair of operatively-connected movable compartments carried by the chest, link connections between said parts actuated by the opening and closing of the lid to automatically move the compartments to open and closed position, a rod connected with one of the links, and a spring mounted upon the rod and acting upon the same to assist both the opening and closing operation.

In testimony that I claim the foregoing as my own I have hereto affixed my signature in the presence of two witnesses.

FRANK JOSHEP SCHWARTZ.
